(57) **CLAIM**

The ornamental design for a novelty bottle cap remover, as shown and described.

DESCRIPTION

FIG. 1 is a front view of a novelty bottle cap remover showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.

The broken lines depict environmental subject matter only and form no part of the claimed design. The phantom lines shown in FIGS. 1-7 define the upper and lower boundaries of the unclaimed cross-hatch environmental subject matter.
